Primary Examiner — Ricky Pham*(74) Attorney, Agent, or Firm* — Taylor J. Ross(57) **CLAIM**

The ornamental design for a microwave pressure cooker, as shown and described.

DESCRIPTION

This application is related to co-pending Ser. No. 13/898,187, filed on May 20, 2013, the contents of which are included herein by reference.

FIG. 1 is a top, front and right side perspective view showing our new design;

FIG. 2 is a top, rear and left side perspective view thereof;

FIG. 3 is a top plan view thereof;

FIG. 4 is a bottom plan view thereof;

FIG. 6 is a rear elevation view thereof;

FIG. 7 is a right side elevation view thereof;

FIG. 8 is a left side elevation view thereof;

FIG. 9 is a cross-sectional view along line 9-9 of FIG. 3; and,

FIG. 10 is a cross-sectional view along line 10-10 of FIG. 3.
